UNITED STATES PATENT OFFICE.

IRA A. MANN, OF PITTSBURGH, PENNSYLVANIA; MARION P. MANN EXECUTRIX OF SAID
IRA A. MANN, DECEASED.

PLUMBING-BOWL FIXTURE.

1,256,918.

Specification of Letters Patent. Patented Feb. 19, 1918.

Application filed May 29, 1914. Serial No. 841,759.

To all whom it may concern:

Be it known that I, IRA A. MANN, a citizen of the United States, residing at Pittsburgh, in the county of Allegheny and State 5 of Pennsylvania, have invented certain new and useful Improvements in Plumbing-Bowl Fixtures, of which the following is a specification.

The invention relates to plumbing bowl fixtures such as those of closets, sinks, lavatories, and the like, and particularly to wall bowls and the method of supporting them from the piping in the wall or partition against which the bowl is applied. The invention 10 has for its primary objects; the provision of a construction with an inclined outlet sleeve or coupling in which improved means are employed for securing an adjustable sealing joint between the sleeve and the surrounding bowl; the provision in a device 15 of the character specified of improved means for securing the bowl against movement longitudinally of the inclined sleeve; the provision of improved means for securing a bearing support between the wall of the outlet passage of the bowl and the inclined coupling; the provision of an arrangement 20 whereby the supply valve or valves and their box are supported on the piping and readily 25 accessible for repair; and in general the provision of a simplified bowl supporting means of great rigidity and capable of ready adjustment. Certain embodiments of the invention are illustrated in the accompanying 30 drawings, wherein—

Figure 1 is a side elevation, partly in section, showing the application of my invention to a lavatory, Fig. 2 is a section on the line II—II of Fig. 1, Fig. 3 is a face 40 view of the valve box and its supporting means, Fig. 4 is a partial side elevation and partial section through a modified construction, Fig. 5 is a plan view of a clamp of slightly different type from that shown in 45 Fig. 4, Fig. 6 is a side elevation partly in section, of a modification showing the application of the invention to a closet, and Fig. 7 is a plan view of means for connecting the bowl to the piping in the wall, the bowl 50 itself being removed.

Referring first to the construction of Figs. 1, 2, and 3, 1 is a lavatory bowl which may be of any approved type; 2 is the outlet stopper operated from the handle 3; 4 is the 55 upwardly inclined outlet passage leading

from the device; 5 is the upright outlet piping located in the wall or partition; 6 is a box carrying the inlet valve 7 which is controlled by the handle 8; and 9 is the spigot leading from the valve 7 into the bowl. 60

Connected with the T 10 forming a part of the outlet piping is a downwardly inclined coupling 11, such coupling extending to a point adjacent the lower end of the passage 4 and abutting at its lower end against 65 the shoulder 12. The coupling 11 fits loosely in the outlet piping 4, and a tight joint is secured by the use of a compressible gasket 13 which surrounds the coupling. In order to hold the gasket against downward movement with respect to the coupling a collar 14 is screw threaded upon the end of the coupling, thus providing a shoulder against 70 which the gasket contacts.

The compressing of the gasket 13 in order 75 to secure a tight joint is accomplished by means of a sleeve 15 which telescopes over the coupling 11 and engages at its front edge with the gasket 13. This sleeve is provided with a flange 16 and through perforations 80 in this flange are threaded the securing bolts 17 which perform the double function of adjusting the sleeve 15 and of supporting the bowl. The bolts 17 extend through flanges 18 forming a part of the bowl structure, and 85 are provided at their ends with holding nuts 19. The other ends of the bolts 17 pass through the outturned ends of a yoke 20, which yoke, as indicated in Fig. 1, extends 90 around the piping in the wall at the upper edge of the T 10.

As indicated in Fig. 2, the threaded ends of the bolts 17 which carry the nuts are provided with longitudinal slots and the nuts themselves are similarly slotted to receive 95 keys 21. When these keys are in the position indicated in Fig. 2, and the nuts 19 are turned, the bolts 17 turn with the nuts, and the sleeve 15 is adjusted forwardly to compress the gasket 13. On the other hand 100 when it is desired to adjust the position of the bowl with respect to the wall, without operating the sleeve 15, the keys 21 are removed from position, and on screwing up the nuts 19 the bowl is adjusted toward the 105 yoke 20 without producing any change in the relative position of the yoke 20 and the sleeve 15. This last operation of course tends to tighten the gasket 13, but this can be compensated for if desired, before the 110

operation, by positioning the keys 21 and moving the nuts so as to back the sleeve 15 out slightly.

It will be seen that the foregoing arrangement is advantageous in that it provides a water tight joint below the level of the water in the trap, and one which can be adjusted and tightened without inconvenience and without the necessity of removing the 10 bowl from the wall. A further advantage results from the fact that the gasket 13 provides a yielding support taking the downward thrust due to the weight of the bowl. The support is thus secured at a maximum 15 distance from the wall, relieving the wall itself of the thrust of the bowl.

Movement of the upper portion of the bowl away from the wall is resisted by means of a pair of tension rods 22 which 20 extend through flanges formed upon the rear side of the bowl and secured in place by means of the nuts 23 and 24. The nuts 24 serve to fix the position of the rear of the bowl with respect to the partition and 25 the vertical piping. The other ends of these tension rods 22 extend through forks 25 (Fig. 3) in the end of the arm 26, such arm being carried by a half collar 27 (Fig. 1) which partially surrounds the pipe 5. 30 This half collar 27 is bolted to another half collar 28, thus providing a supporting clamp upon the pipe 5. The ends of the rods 22 are secured in the forks 25 by means of the squared nuts 29 slotted to fit slidably 35 but non-rotatably in the said forks. By these means the rods 22 can be adjusted in and out as desired, and the position of the rods can be shifted laterally to suit requirements. The loose fit of the coupling in the 40 passage 4 permits the bowl to swing around the gasket as a fulcrum when the tension rods are adjusted. This feature of adjustment takes care of any sagging, and of any warpage accruing in turning the ware, such 45 warpage making it impossible to attach the bowls by standard uniform fittings not having the feature of adjustment. The brace 1^a prevents warping of the trap portion of the bowl therebeneath.

50 Mounted above the rods 22 is the valve box 30, such box being secured in position by means of the brackets 31^a bolted to the half collar 27, and carried by the same bolts which hold the two parts of the clamp together. The box 30 can be arranged to hold any desired number of valves 7, the box as indicated in Fig. 3 being designed to hold three valves, the stems whereof pass through the holes 31 in the lid of the box. The lid is 55 provided with perforations 32 to take plaster when so desired, but a solid covering 33 can be used upon this lid, being held in position with the lid itself by means of the screws 34.

In Fig. 4 a modified construction is illustrated, the type of bowl being somewhat dif-

ferent and the method of adjusting the gasket being different. In this structure 1' is the bowl, 5' is the outlet piping, 2' is the outlet plug, and 11' is the outlet coupling leading from the bowl to the piping 5'. The gasket 13' is operated by means of a sleeve 15', such sleeve being provided with an inwardly directed flange 16' through which are threaded adjusting sleeves 35. Through these sleeves 35 extend the threaded ends 36 of the 75 yoke 20', such threaded ends carrying the nuts 19'. Threaded upon the adjusting sleeves 35 are the adjusting nuts 37, which nuts when once screwed into the position illustrated in Fig. 4 are non-rotatable with 80 respect to the sleeve 35. It will be seen that when nuts 19' are loosened the nuts 37 can be turned, thus moving the sleeve 35 and adjusting the sleeve 15' in and out. When it is desired to adjust the position of the 85 bowl with respect to the wall the nuts 19' are operated.

In Fig. 5 a clamp for the piping 5 is illustrated, which clamp consists of two parts 39 and 40 bolted together over the pipe 90 and each provided with a forked arm, 41 and 42. This clamp may very conveniently be used when there are bowls on opposite sides of the same partition, the one clamp thus serving to carry the tension rods 22 95 from each bowl.

In Figs. 6 and 7 a modified construction is illustrated, such modified construction being particularly applicable to use in cases where the bowl is a closet bowl. In this 100 construction the bowl 1^a is provided with an upwardly directed outlet passage leading to the piping 5^a, and an inclined coupling 11^a is employed through which an annular flushing jet is admitted via the 105 passage 43. The gasket 13^a is used intermediate the coupling and the interior of the outlet passage, the same as in the other construction, and this gasket 13^a is adjusted by means of the sleeve 15^a having the outwardly turned flanges 18^a through which are threaded the adjusting bolts 17^a. These bolts 17^a extend at their upper ends through an angular plate 44, and at their lower ends are provided with the nuts 19^a. The 115 threaded ends of the bolts 17^a and the nuts are slotted as in the construction of Fig. 1, and keys 21^a are employed just as in the construction of Fig. 1. The operation of adjusting the sleeve 15^a and the bowl is 120 therefore precisely the same as in the apparatus of Figs. 1 and 2. The angular plate 44 is supported from the piping 5^a by means of a yoke 20^a extending around the piping and through the plate as indicated 125 in Figs. 6 and 7. The bowl 1^a is provided at its upper rear portion with a flange 45, and tension bolts 46 are provided intermediate this flange 45 and one of the flanges of the angular plate 44. Any sag in the bowl 130

may be taken up by means of the tension connection 46, such connection performing the function of the tension connection 22 in the construction of Fig. 1. In this construction the gasket 13² takes the main portion of the weight of the bowl and acts as a fulcrum about which the bowl moves when the tension connections 46 are operated to level the bowl. The angular plate 44 is preferably connected with the coupling 11² by means of the lug 47 which projects through a slot in the plate 44, such lug being held in position by means of a cotter pin 48. The plate 44 is thus securely supported against movement. In this and the other types of construction the yoke 20² extending around the vertical piping, tends to relieve the strain on the coupling.

What I claim is:

- 20 1. In combination, a wall bowl having an upwardly inclined outlet passage, upright piping in the wall, an inclined coupling lying in said passage, and connected with the said piping, a gasket between the wall 25 of the inclined outlet passage and the exterior of the coupling, stop means on the coupling, a sleeve lying between the coupling and the wall of the outlet passage and 30 slidably longitudinally of the coupling and adapted to press the gasket against the said stop means, and screw means operable from the front of the bowl for adjusting the sleeve.
2. In combination, a wall bowl having an 35 upwardly inclined outlet passage, upright piping in the wall, an inclined coupling lying in the said passage and connected with the said piping and having a shoulder at its lower end, a gasket engaging said 40 shoulder, a member surrounding the coupling slidably longitudinally thereof and engaging the gasket, and screw means operable from the front of the bowl for adjusting the sleeve to compress the gasket.
- 45 3. In combination, a wall bowl having an upwardly inclined outlet passage, upright piping in the wall, an inclined coupling lying in the said passage and connected with the said piping, a yoke fitting around the 50 piping, screw connections between the yoke and bowl, a gasket between the wall of the outlet passage and the coupling, a member fitting slidably around the coupling and engaging the gasket, and means whereby the 55 said member is moved along the coupling by the said screw connections.

4. In combination, a wall bowl having an upwardly inclined outlet passage, upright piping in the wall, an inclined coupling 60 lying in the said passage and connected with the said piping, a yoke fitting around the piping, a gasket between the wall of the outlet passage and the coupling, a member fitting slidably around the coupling and engaging the gasket, threaded connections ex-

tending from the yoke through the said member, and means for securing the threaded connections to the bowl and for adjusting the said member longitudinally of the coupling to compress the gasket. 70

5. In combination, a wall bowl having an upwardly inclined outlet passage, upright piping in the wall, an inclined coupling lying in the said passage and connected with the said piping, a yoke fitting around the 75 piping, a gasket between the wall of the outlet passage and the coupling, a member fitting slidably around the coupling and engaging the gasket, threaded connections extending from the yoke through the said 80 member and through portions of the bowl, nuts on the threaded connections, and means for securing the nuts against rotation with respect to the threaded connections whereby such threaded connection may be rotated by 85 the nuts and the said member adjusted longitudinally of the coupling to tighten the gasket.

6. In combination, a wall bowl having an upwardly inclined outlet passage, upright 90 piping in the wall, an inclined coupling lying in the said passage and connected with the said piping, a gasket between the wall of the inclined outlet passage and the exterior of the coupling and adjacent the lower end 95 of the coupling, means adjustable longitudinally of the coupling to tighten the gasket, and a tension connection between the piping and the bowl above the coupling.

7. In combination, a wall bowl having an 100 upwardly inclined outlet passage, upright piping in the wall, an inclined coupling lying in the said passage and connected with the said piping and having a bearing contact adjacent its lower end with the bowl, 105 and an adjustable tension connection between the piping and the bowl above the said coupling.

8. In combination in a bowl fixture having an upwardly inclined outlet passage 110 leading from the lower portion of the bowl fixture, a metal outlet coupling lying in the outlet passage, a gasket around the coupling and lying below the water level in the fixture, means fitting over the coupling and 115 slidably longitudinally thereof for tightening the gasket, and screw means operable from the front of the bowl for adjusting the said means.

9. In combination, a wall bowl having an 120 upwardly inclined outlet passage, upright piping in the wall, an inclined supporting coupling lying in said passage and connected with said upright piping, and a yoke extending around the vertical piping and having 125 its ends connected to the bowl, the said ends extending longitudinally of the coupling.

10. In combination, a wall bowl having an upwardly inclined outlet passage, up- 130

right piping in the wall, a supporting coupling fitting loosely in said passage, and carried by the vertical piping, and having its lower end engaging the walls of the outlet passage and acting as a fulcrum support of the bowl, and an adjustable tension connection between the upright piping and the bowl above the coupling for swinging the bowl about the said lower end of the coupling.

11. In combination, a wall bowl having an upwardly inclined outlet passage, upright piping in the wall, a supporting coupling fitting loosely in said passage, and carried by the vertical piping, and having a gasket on its lower end engaging the walls of the outlet passage and acting as a fulcrum support of the bowl, and an adjustable tension connection between the upright piping and the bowl above the coupling for swinging

the bowl about the said lower end of the coupling.

12. In combination, a wall bowl having an upwardly inclined outlet passage, upright piping in the wall, a supporting coupling fitting loosely in said passage, and carried by the vertical piping, and having a gasket on its lower end engaging the walls of the outlet passage and acting as a fulcrum support of the bowl, adjustable tension connections between the upright piping and the bowl above the coupling, and means for tightening the said gasket.

In testimony whereof I have hereunto signed my name in the presence of the two subscribed witnesses.

IRA A. MANN.
